UNITED STATES PATENT OFFICE.

GEORGE L. THORNTON, OF HUNTINGTON, WEST VIRGINIA.

ELECTRIC WELDING-TOOL.

1,211,009.

Specification of Letters Patent. Patented Jan. 2, 1917.

Application filed October 19, 1916. Serial No. 126,534.

To all whom it may concern:

Be it known that I, GEORGE L. THORNTON, a citizen of the United States of America, and a resident of Huntington, county of Cabell, State of West Virginia, have invented certain new and useful Improvements in Electric Welding-Tools, of which the following is a full and clear specification.

The object of this invention is to provide 10 a simple and inexpensive hand or manual tool for holding the electrode used in electric-welding processes, and the invention consists of certain novel features of construction hereinafter described and claimed.

15 In the drawing—Figure 1 is a side elevation and Fig. 2 a vertical longitudinal section of a tool embodying my invention.

In the drawing, *a* designates a handle of wood or other insulating material, said 20 handle being hollow throughout its length and being at its forward end screwed on to the externally-threaded end of a copper tube *b*. Extending into the handle from the rear end thereof is the conductor *c* which is attached 25 electrically to the rear end of the tube *b* by means of a suitable screw coupling *d*. In the tube is adapted to slide a copper rod *e*, which is notched at its forward end to engage the welding rod *f*, which rod rests 30 in a notch *g* formed in the tube near its outer end, the arrangement being such that when the rod *e* is pressed outwardly, the rod *f* will be clamped in the notch, while when the rod is drawn inwardly the rod *f* will be free to 35 be disengaged from the tube by passing out through the notch.

The rod *e* is normally pressed outwardly by means of a coil spring *h* confined within 40 the tube *b* between a pair of wooden or other insulating blocks *i*, the inner block resting against the screw plug *d* and the outer plug being normally pressed against the inner end of the clamp rod *e*.

To withdraw the rod *e* to release the welding rod *f*, I provide an angular thumb lever *j*, pivoted between a pair of ears *k* formed on the tube *b* and connected by means of a link *l* to a lug *m* fastened to the rod *e* at a point distant from its rear or inner end, the lug *m* being adapted to work in a slot *n* formed in the tube *b*. To withdraw the rod *e* from contact with the welding rod *f*, it is simply necessary to press the free end of lever *j* toward the handle, this being readily 55 accomplished by means of the thumb of the same hand that grasps the handle *a* in ma-

nipulating the tool, thereby enabling the tool to be readily handled with one hand, leaving the other hand of the operator free for other purposes.

By connecting the tube *b* to one end of the handle only, it will be seen that the grasping part of the handle, for the most part, will be kept cool enough to enable the operator to continuously handle the tool without discomfort. By extending the conductor *c* into the handle a considerable distance before it is connected to the tube *b*, and by using a conductor smaller in diameter than the interior diameter of the handle and also having the rear end of the handle open, I avoid abrupt bending of the conductor at its point of connection with the tube during the handling of the tool and thus greatly prolong the life of the conductor, it being evident that if the tube *b* were extended entirely or substantially through the handle, the handle would not only quickly become too hot to hold, but the conductor would be subject to short bending at the point of connection and would therefore soon become so weakened as to burn out at or near the point of connection with the tube. By arranging the spring *h* back of the clamp rod *e* and mounting it between two heat-protecting blocks *i*, it will be observed that the spring will be prevented from becoming so hot as to destroy its temper, whereby the life of the spring will be greatly prolonged. By making the tube *b* and rod *e* of copper, I avoid all the troubles due to the welding of the rod *f* to the tool; where the welding-rod grasping devices are constructed of weldable metal, a great deal of trouble has been experienced by reason of the rod welding to 95 the tool, thereby rendering it troublesome to dislodge the rod from the tool; these troubles, as stated, are avoided by constructing the rod-grasping devices of non-weldable metal, such as copper.

Having thus described my invention, what I claim is:

1. A tool of the class set forth, comprising a handle hollow throughout its length and open at its rear end, a tube attached 105 to the forward end of the handle and carrying welding-rod grasping devices, and a conductor extending through the handle from the rear and connected to the rear or inner end of said tube at the forward end of 110 the handle, said conductor being smaller in diameter than the interior diameter of the

hollow of the handle, for the purpose set forth.

2. In a tool of the class set forth, the combination of a hollow handle, a tube attached thereto at one end, a conductor attached to the inner end of the tube, rod-grasping devices embodying a slidable rod in the tube, a coil spring inclosed in the tube at the rear end of the rod, heat-insulating devices with-
10 in the tube forming abutments for said

spring, and devices for drawing said rod inwardly against the action of said spring, for the purpose set forth.

In testimony whereof I hereunto affix my signature.

GEORGE L. THORNTON.
